UNITED STATES PATENT OFFICE

2,203,108

REFRIGERATOR FREIGHT CAR

Robert Kent Schwebs, Hortonville, Wis.

Application June 13, 1938, Serial No. 213,421

5 Claims. (Cl. 62—24)

This invention appertains to refrigerator freight cars of the type employed in shipping perishable foodstuffs, and is an improvement on the constructions shown in my Patents No. 5 2,136,894 of November 15, 1938, and No. 2,159,406 of May 23, 1939.

In my two mentioned patents, I disclosed various means for continuously circulating air through the refrigerator car, while the car is in transit. This means consisted of fans driven in various manners for drawing air up through the ice bunkers from the floor of the car, and forcing the same over the goods in the car to the end, that a continuous cycle of conditioned air would 10 be passed through the perishable articles, so that the perishable articles could be maintained at the same temperature at all points in the car.

While the means employed operated admirably within certain limits, I have found that there was 20 a decided tendency for a large portion of the air, instead of being drawn down through the articles and up through the bunkers, to flow around the upper sides of the car and over the top of the bunker, and then to the fans. Naturally, this flow of air did not accomplish the desired conditions for cooling.

It is, therefore, one of the salient objects of my invention to provide means for automatically closing the space above the partition forming 30 the ice bunker on each side of the power-driven fan, whereby, when the fan is in operation, the air will not be drawn around the sides of the car and over the top of the bunker, but will be drawn down through the body of the car and up 35 through the bunker.

Another important object of my invention is the provision of members of any desired character for closing the space between the bunker partition and the roof of the car on each side of 40 the air-circulating fan, with means for automatically closing said members as soon as the fan starts in operation, means being provided for holding the members open at all other times.

A further object of my invention is to provide 45 means for employing fluid under pressure for automatically closing the ventilator shutters over the bunkers when fluid under pressure is utilized for driving the air-circulating fans, so that when the pressure is employed for operating fan, said pressure will synchronously operate and close the ventilating shutters.

With these and other objects in view the invention consists in the novel construction, arrangement, and formation of parts, as will be 50 hereinafter more specifically described, claimed,

and illustrated in the accompanying drawings, in which drawings:

Figure 1 is a fragmentary, longitudinal, sectional view through a refrigerator freight car, showing one form of my improved appliance incorporated therewith. 5

Figure 2 is a transverse, sectional view through the car, taken substantially on the line 2—2 of Figure 1, looking in the direction of the arrows, showing my improved appliance incorporated 10 therewith.

Figure 3 is an enlarged horizontal sectional view through the car, taken substantially on the line 3—3 of Figure 2, looking in the direction of the arrows, illustrating one means for automatically opening and closing the ventilating 15 shutters, the shutters being shown in their closed position.

Figure 4 is a view similar to Figure 3, showing the ventilating shutters in their open position. 20

Figure 5 is a detail, vertical, sectional view, taken substantially on the line 5—5 of Figure 2, looking in the direction of the arrows.

Figure 6 is an enlarged, detail, sectional view, taken substantially on the line 6—6 of Figure 3, 25 looking in the direction of the arrows illustrating the pressure means for closing the ventilating shutters.

Referring to the drawings in detail, wherein 30 similar reference characters designate corresponding parts throughout the several views, the letter R generally indicates a refrigerator freight car, and the same embodies the usual insulated body 10 having formed at each end thereof bunkers 11. These bunkers are formed by trans- 35 verse partitions 12, which extend entirely across the car. The partitions terminate short of the roof of a car, as can be clearly seen by referring to Figures 1 and 2 of the drawings. The partitions include vertical uprights 13, which are arranged in spaced relation, and the uprights extend entirely to the roof of the car. The space above the partition and between the uprights 13 40 form large ventilating openings or air passageways 14. The bunkers 11 are adapted to receive ice during the warm seasons of the year, and heating devices during cold seasons of the year. The ice or the heaters, as the case may be, rests 45 on a grating 15 above the level of the car-floor. The body of the car is likewise provided with a suitably perforated or reticulated false bottom 16, on which the foodstuffs to be shipped are placed. The partition 12 terminates at the grating 15 and false bottom 16, but the uprights 50

55

13 of the partition extend from the floor to the roof, as previously described.

An air-circulating fan 17 of the desired capacity is arranged above the partition 12 at the central portion of the car, and is employed for drawing the air up through the bunkers over the top of the foodstuffs, down through the foodstuffs, and up into the bunkers below the false bottom 16 and the grate 15. By employing the air-circulating fan 17, a continuous cycle of air can be caused to flow in the car.

The air-circulating fan 17 can be driven in any preferred manner, such as by an electric motor, an internal combustion engine, or by means shown in my two mentioned pending applications. For the purpose of illustration, I have shown the air-circulating fan 17 driven substantially in the same manner as in my Patent No. 2,136,894 of November 15, 1938, and thus the fan is driven from a turbine 18. A suitable liquid, such as oil under pressure, is employed for actuating the turbine, and this oil can be placed under pressure from a rotary pump 19 driven from a friction drive wheel 20, which is normally held in contact with one of the car-wheels. The pump takes the fluid from a reservoir tank 21, and forces the same through a pipe line 22, which leads to the turbines for the air-circulating fans located at the opposite ends of the car.

30 A pipe 22 is also connected by a pressure relief valve 23 with the reservoir tank 21, whereby if the pressure exceeds a predetermined degree the same can by-pass into the reservoir tank and the valve can be adjusted to the desired pressure. 35 The return pipe 24 leads from the turbine 18 back to the reservoirs 21.

I have found that in actual practice the air tends to flow along the sides of the car at the top thereof and into and over the ice bunkers. 40 It is then forced into the central part of the car by the air-circulating fan. In order to overcome this difficulty I propose to provide means 25 for closing the space between the roof of the car and the top of the partition 12 on each side of 45 the air-circulating fan 17. I also propose to automatically open and close this means. Thus, when the fan is in operation, the space on the opposite sides of the fan will be closed, and air will be positively drawn through the bunkers, 50 into the body of the car, and down through the perishable articles.

The space above the partition on each side of the fan can be automatically opened and closed in various manners, and I have only illustrated one 55 form for automatically opening and closing the same. As I have shown the air-circulating fans driven by turbines, which are in turn operated by liquid under pressure, I employ liquid under pressure to automatically close the ventilating shutters.

60 In the present instance I have illustrated my ventilating shutters to consist of a plurality of vertically disposed slats or louvres 26, which are rockably mounted on vertical pivots 27. All of 65 the slats or louvres are connected together by means of an operating rod 28, which extend transversely across the car. This rod 28 is connected by means of links 29 with the slats or shutters, and the rod is guided in its movement 70 by bearing brackets 30. Obviously, by shifting the rod 28, the slats or louvres can be opened or closed.

Adjacent to the turbine I position a cylinder 31, in which is mounted a piston 32. The piston 75 32 has connected therewith a piston rod 33, which

in turn is connected to the operating rod 28. An expansion spring 34 is coiled about the piston rod 33 and is confined between one end wall of the cylinder and the piston 32. The spring 34 is so arranged as to hold the piston 32 at one end of the cylinder and the rod in such a manner as to hold the slats or louvres open. The cylinder 31 can be connected with the liquid under pressure by means of a pipe 35, and the liquid under pressure, when admitted thereto, forces the piston 10 against the tension of the spring 34 to the opposite end of the cylinder, and moves the rod 28 in such a manner as to close these slats or louvres. Obviously, pressure is only admitted to the cylinder 31 when the pump 19 starts in operation to 15 supply pressure to the turbine 18. Thus, when the car is standing still, and the air-circulating fan is not in operation, the car will be cooled in the ordinary manner and the air will circulate in the usual way.

20 My invention relates broadly to automatic means for opening and closing the space above the bunker partition on each side of the ventilating fan, and it is to be understood that any desired means other than pivoted slats or louvres 25 can be employed.

Changes in details may be made without departing from the spirit or the scope of this invention, but what I claim as new is:

1. In a refrigerator car, a body having side 30 walls, an end wall, a roof, a floor, and a false bottom for said floor, a partition extending transversely across the body adjacent to the end wall terminating short of the roof and at the false bottom, said partition defining in conjunction 35 with the side and end walls an ice bunker, an air-circulating fan disposed above the partition at the central portion thereof for drawing air up through the ice bunker and into the body of the car adjacent to the roof, means for operating the fan, ventilators for opening and closing the space between the partition and the roof on opposite sides of the fan, means normally maintaining the ventilators in open position, and means for automatically closing said ventilators 40 against the tension of said last-mentioned means when the fan is in operation.

2. In a refrigerator car, a body having side 45 walls, an end wall, a roof, a floor, and a false bottom for said floor, a partition disposed transversely across the body adjacent to the end wall extending from the false bottom toward said roof, said partition terminating short of the roof and forming in conjunction with the side and end walls an ice bunker, an air-circulating device 50 disposed above the partition at the central portion thereof for drawing air up through the ice bunker and forcing the same into the body of the car adjacent to the roof, a fluid driven motor for operating the device, ventilators for controlling 55 the space between the partition and the roof on opposite sides of the device, means normally holding the ventilators in open position, and means operated by the fluid for the motor for closing 60 said ventilators when the motor is in operation.

3. In a refrigerator car, a body having side 65 walls, an end wall, a roof, a floor, and a false bottom for said floor, a partition disposed transversely across the body adjacent to the end wall terminating short of the roof, defining an ice 70 bunker in conjunction with the side and end walls, an air-circulating fan disposed above the partition for drawing air up through the ice bunker and into the body of the car adjacent to the roof, a fluid driven motor for operating the 75

- fan, a ventilator for controlling the space between the partition and the roof of the car on each side of the fan, said ventilators including a plurality of pivoted slats, a single operating rod for actuating all of the slats synchronously, a cylinder, a piston in said cylinder, means operatively connecting the piston to the rod, spring means normally holding the piston and the rod in one position for holding the slats open, and means connecting the cylinder with the source of fluid for the motor whereby to cause the operation of the piston against said spring means when the motor is in operation to move the slats to a closed position.
4. In a refrigerator car, a body having side walls, an end wall, a roof, a floor and a false bottom for said floor, a partition disposed transversely across the body adjacent to the end wall extending substantially from the false bottom and terminating short of the roof and forming in conjunction with the side and end walls a bunker compartment separate from the lading compartment of the car, an air circulating device in the space between said partition and said roof for drawing air from one of said compartments to the other of said compartments, a fluid driven motor for operating said device, ventilators for controlling the portion of the space between said partition and said roof not occupied by said device, means for normally holding the ventilators in open position, and means operated by the fluid for the motor for closing said ventilators when the motor is in operation.
5. In a refrigerator car, a body having side walls, an end wall, a roof, a floor and a false bottom for said floor, a partition disposed transversely across the body adjacent to the end wall extending substantially from the false bottom and terminating short of the roof and forming in conjunction with the side and end walls a bunker compartment separate from the lading compartment of the car, an air circulating device in the space between said partition and said roof for drawing air from one of said compartments to the other of said compartments, a fluid driven motor for operating said device, ventilators for controlling the portion of the space between said partition and said roof not occupied by said device, a cylinder, a piston within said cylinder operatively connected to said ventilators and an expansion spring positioned to hold the piston at one end of the cylinder and thus normally hold the ventilators in open position, and means connecting the cylinder with the source of fluid for the motor whereby to cause the operation of the piston against said spring when the motor is in operation to move the ventilators to closed position.

ROBERT KENT SCHWEBS. 30
